CAR TRUCK

James A. Shafer, East Cleveland, Ohio, assignor
to National Malleable and Steel Castings Com-
pany, Cleveland, Ohio, a corporation of Ohio

Application May 10, 1935, Serial No. 20,711

14 Claims. (Cl. 105—197)

This application is a continuation-in-part of my application Serial Number 581,550, filed December 17, 1931 and relates to improvements in car trucks.

5 An object of this invention is to provide means for easily and effectively taking care of and compensating for wear between the bolster and side frame of a truck.

Another object is to provide a replaceable member, or members, adapted to compensate for the wear between bolster trunnions or dowels and the side frame of a truck. Further objects will be apparent from the following description of the invention and of the preferred embodiment thereof, illustrated in the drawing, in which:

Figure 1 is a horizontal sectional view showing a portion of a side frame embodying my invention.

Figure 2 is a vertical sectional view showing one bolster dowel in place and taken on a line transverse of the side frame.

Figure 3 is a plan view of bushing member embodying my invention.

25 In Figure 1, the dotted line 2 indicates the general outline of the end portion of the bolster extending through a hole or window in a side frame 3 and having downwardly depending dowels or trunnions 4. It will, of course, be understood that the bolster at its opposite end has similar dowels for engaging with the opposite side frame of the truck, but a description of the cooperation between one end of the bolster and associated side frames will suffice for an understanding of my present invention. The bolster and side frame here shown are of the same type as illustrated in my application No. 581,550, and in my Patent No. 1,973,664, dated September 11, 1934. The dowels 4 preferably rest on the spring caps 5 on top of the springs 6, which in turn are supported by the bottom part of the side frame (not shown). Suitable plugs 7 may be carried on the spring caps to assist in keeping the springs in place. The dowels extend through holes 8 in the shelf 9 of the side frame and since the bolster, through the dowels on its opposite ends, ties together the two opposite side frames of the truck, a considerable amount of wear takes place between said dowels and the adjacent rims of the 50 holes through which said dowels extend.

In carrying out my invention I provide bushing members 10 between the dowels or trunnions 4 and adjacent portions of the side frame; the holes 8 being preferably cut away, as shown, to enable the insertion of said bushing members,

which are shown arcuate in form. Each bushing member is in the shape of an inverted L in cross section, as best seen in Figure 3, so that the top brim thereof may serve to keep it from sliding or falling down in the hole. Any other suitable shape may, of course, be used which would accomplish this purpose and the hole 3 could be suitably countersunk, cut out or notched to conform to the shape of the bushing member.

As illustrated in the drawings, Figure 1, the bushing members may extend a little more than half way around the dowels to form an arc of more than 180°. A bushing is thereby provided that may be readily sprung into place, insuring a tight, secure fit. The plates 11 supporting the upper springs 12 on the side frame shelf 9 overlap the bushing members, as clearly shown in Figure 1, and serve as additional means for holding said members securely in place. A particular advantage of these bushings, which are slightly more than semi-circular, is their interchangeability. The major wearing surface between bolster dowels and side frames occurs on the sides toward the bolster proper, as shown at the angle A in Figure 1. After a car has been in use for some time, the bushings will be worn much more over this area than in any other portion. The bolster may then be jacked up or raised, the side frames removed, and the two bushing members of each side frame interchanged. This necessarily brings the least worn portions into the position of greatest wear and turns the worn parts to a position where high wear resistance is not needed. The bolster dowels may also each be provided with a tubular bushing member 13, which is preferably fitted tightly over the dowel, but is also prevented from accidentally coming off by the spring cap 5. This bushing member may be similarly rotated to bring fresh, substantially unworn portions to the inner side of the dowels over the angle A. It will be readily apparent that by this assembly the bolster dowels and associated wearing parts may be rebushed without the addition of any new parts, which is particularly helpful when repairs are needed at some point remote from the usual repair shop.

My invention, however, is distinctly not limited to interchangeable bushing members, but such members may be of any suitable size, so long as they take care of the major portion of wear. For example, bushing member 10 may be of an arc less than 180° and of a size to facilitate its insertion and removal more easily, such as described in my prior application S. N. 581,550, aforesaid.

Such bushing members may also be designed so that they may be inserted without raising the bolster as high as would be required in the case of the embodiment shown in the drawings.

5 The terms and expressions which I have employed are used as terms of description and not of limitation, and I have no intention, in the use of such terms and expressions, of excluding any equivalents of the features shown and described 10 or portions thereof, but recognize that various modifications are possible within the scope of the invention claimed.

What I claim is:

1. In apparatus of the class described, the combination of a side frame having openings therein, depending bolster dowels integral with the bolster projecting into said openings and replaceable means for compensating for wear between said dowels and said side frame, said means comprising removable members interspersed between said dowels and the walls of the openings in said side frame inward of said dowels.

2. In apparatus of the class described, the combination of a side frame having openings therein, depending bolster dowels integral with the bolster projecting into said openings, and replaceable means for compensating for wear between said dowels and said side frame, said means comprising removable members carried by said dowels.

3. In a truck for railway cars, the combination of a side frame having a bolster opening, a spring seat beneath said bolster opening, said spring seat having openings therein, a bolster extending into said bolster opening and provided with integral dowels projecting through said openings in said spring seat, spring means on said seat for supporting said bolster, and means held in place by said spring means for compensating for wear between said dowels and the walls of said openings 40 in said spring seat.

4. In a truck for railway cars, the combination of a side frame having a bolster opening, a spring seat beneath said bolster opening, said spring seat having openings therein, a bolster extending into said bolster opening and provided with integral dowels projecting through said openings in said spring seat, and means for compensating for wear between said dowels and the walls of said openings in said spring seat, said means comprising removable members interposed between said dowels and said walls of said openings and arranged for interchanging with each other in predetermined complementary positions.

5. In a railway car truck, the combination of a side frame having a bolster opening, a shelf beneath said bolster opening, said shelf having an opening therein, a bolster extending into said bolster opening and provided with an integral dowel projecting through said opening in said shelf, and removable means held in place by said bolster for compensating for wear between said dowel and the walls of said opening in said shelf.

6. In a railway car truck, the combination of a side frame having a bolster opening, a shelf beneath said bolster opening, said shelf having an opening therein, a bolster extending into said bolster opening and provided with a dowel projecting through said opening in said shelf, and means for compensating for wear between said dowel and the walls of said opening, said opening communicating throughout a portion of its periphery with a recess in said shelf, said compensating means comprising a removable member having a horizontal portion adapted to fit into

said recess and a depending portion adapted to extend between a wall of said opening and a portion of said bolster dowel.

7. In a railway car truck, the combination of a side frame having a bolster opening, a shelf beneath said bolster opening, said shelf having an opening therein, a bolster extending into said bolster opening and provided with a dowel projecting through said opening in said shelf, and means for compensating for wear between said dowel and the walls of said opening in said shelf, said opening communicating with an arcuate recess in said shelf, and said compensating means comprising a removable arcuate member L-shaped in cross section, one portion of which 15 seats in said recess and another portion of which extends between the wall of said opening and a part of said bolster dowel.

8. In a railway car truck, a side frame having a bolster opening, a bolster having an end thereof extending into said opening, a dowel on said bolster and means for compensating for wear between portions of said side frame and dowel, said means comprising a bushing having a pair of intersecting concentric arcuate flanges and positioned on said side frame between the latter and the dowel.

9. In a railway car truck, a side frame having a bolster opening, a bolster having an end thereof extending into said opening, a dowel on said bolster, and means for compensating for wear between portions of said side frame and dowel, said means comprising a bushing consisting of a segmental arcuate element L-shaped in cross section, said shim being positioned on said side frame 35 between the latter and the dowel.

10. In a truck for railway cars, a side frame, a bolster having dowels projecting through an opening in said side frame, an arcuate bushing member in said opening positioned at the area 40 of greatest wear between the walls of said opening and said bolster dowels.

11. In a truck for railway cars, a side frame, a bolster having dowels projecting through an opening in said side frame, an arcuate bushing 45 member of greater than 180° in said opening positioned at the area of greatest wear between the walls of said opening and said bolster dowels.

12. In a truck for railway cars, a side frame, a bolster having dowels projecting through an opening in said side frame, an arcuate bushing member of greater than 180° in said opening, only 50 a portion of which is positioned at the area of greatest wear between the walls of said opening and said bolster dowels.

13. In a truck for railway cars, a side frame, a bolster having dowels projecting through an opening in said side frame, an arcuate bushing member in said opening positioned at the area of greatest wear between the walls of said opening 60 and said bolster dowels, and bushing members on said dowels cooperating therewith.

14. In a railway car truck a side frame having a bolster opening, a bolster having an end thereof extending into said opening, and means for compensating for wear between portions of said side frame and bolster, said means comprising a shim consisting of a segmental arcuate element L-shaped in cross section and including a horizontal flange, said shim being positioned on said side frame between the latter and the bolster with the horizontal flange thereof engaging a horizontal supporting surface on said side frame.
